TYPEWRITING MACHINE

Alfred G. F. Kurowski, Brooklyn, N. Y., assignor
to Underwood Elliott Fisher Company, New
York, N. Y., a corporation of Delaware

Application January 11, 1937, Serial No. 119,945

13 Claims. (Cl. 197—63)

This invention relates to typewriters, and more especially to those having a letter-space feed rack on the carriage and a pinion-ratchet escapement mechanism on the frame. An occasional overthrow of the carriage, when the carriage is returned and banked against the right-end margin-stop, thereby causing the first type impression in a line on a copy-sheet to be made one letter-space to the left of the vertical line on the worksheet predetermined by the margin-stop setting, takes place when the carriage attains an unusually great momentum during return. Sometimes also, when the carriage is returned and banked against the right-end margin-stop, the carriage-rack jumps off from the escapement pinion and falls back into engagement with the pinion one tooth away from the original contact tooth and therefore the carriage is left in such a position that the initial type impression is made one letter-space to the right of the initial letter-space predetermined by the margin-stop setting. This error of setting to the extent of one letter-space at the beginning of a line sometimes occurs in typewriters having an electrical automatic carriage return and a large carriage having rearward extensions in which a twisting movement of the carriage may take place when banking.

A feature of this invention is broadly a device to assure that every return of the carriage on a typewriter is exactly to the initial letter-space at the beginning of a line predetermined by the setting of a margin-stop.

Another feature of this invention is a mechanism automatically actuated by a margin-stop for locking concomitantly the escapement pinion against overthrow of the carriage when the carriage is returned, or in other words against setting the carriage for type impressions one letter-space to the left of the position predetermined by the margin-stop for the succeeding line of typing.

A feature of this invention is broadly, in a typewriter having a pivotally suspended letter-space feed rack and an escapement pinion, a device for preventing the rack from jumping out of mesh with the pinion, in the banking position of the carriage.

Another feature of the invention is a mechanism automatically actuated by a margin-stop for locking concomitantly the feed rack in mesh with the escapement pinion when the carriage is returned and thereby preventing the setting of the carriage for type impressions one letter-space to the right of the position predetermined

by this margin-stop for the first letter-space in the next succeeding line of typing.

Another feature of the invention is the provision of means concurrently operated by a margin-stop for both locking the escapement pinion against overthrow and for locking the carriage letter-space feed rack in mesh with the pinion to retard jumping of the rack, or in other words to prevent the carriage return to a position either one letter-space to the left or one letter-space to the right of the printing position at the left of a copy-sheet predetermined by the margin-stop.

Another feature of the invention is a device, including a margin-stop that is movable with the carriage in letter-space feeding direction, which is actuated by the margin-stop and which includes a pawl movable into engaging position with a ratchet wheel on the escapement pinion shaft and which includes a hook that simultaneously lockingly engages the letter-space feed-rack to hold the rack in mesh with the escapement pinion.

One embodiment of the invention is applied to a typewriter having an electrical automatic carriage return and in which a margin-stop may be mounted on a banking rod that moves a bell-crank to actuate the electrical return mechanism. A crank-shaft may extend rearwardly from the pivot mounting of the bell-crank in the frame to the rear and actuate a slidible arm which in turn actuates both a pawl that locks the escapement pinion against overthrow and a hook that holds down the carriage letter-space feed-rack in mesh with the pinion, to prevent jumping of the carriage. A ratchet wheel may be mounted on the inner or forward end of the escapement pinion shaft for engagement with the locking pawl and may have a tooth for each letter-space on the typewriter.

Other features and advantages will herein-after appear.

In the accompanying drawings,

Figure 1 is a perspective view with parts of the typewriter broken away.

Figure 2 is a front elevation of the escapement mechanism with the carriage in the extreme return position before the carriage drops back.

Figure 3 is a side elevation with parts broken away.

Figure 4 is a front elevation of the escapement mechanism showing in normal position a part of the supplemental ratchet wheel mounted on the pinion shaft and the locking pawl which is

engageable with this supplemental ratchet to lock the pinion against overthrow, with parts broken away.

Figure 5 is a sectional elevation of the escapement pinion and the carriage-overthrow-prevention ratchet wheel.

Figure 6 is a perspective view of one embodiment of the invention and the cooperating parts of a typewriter, in locking engagement.

Figure 7 is a diagrammatic view of a carriage in banking position showing the twisted position, exaggerated in dot-and-dash cutlines, due to great carriage-return momentum.

Figure 8 is a view similar to Figure 6 but showing only the left end of the device in non-locking relationship to the escapement pinion and the carriage rack.

A heavy duty typewriter frame 10 is mounted on the usual feet 11 and supports a reciprocatorily mounted platen carriage 12 in which is rotatably mounted a cylindrical platen 13, over which is fed a copy-sheet 14 upon which upper and lower case type 15 imprint when keys 16 are struck by an operator. A spring drum 17 winds a strap 18, fastened on an arm 81 depending from the carriage 12, to feed the carriage 12 in writing direction. The frame 10 has a letter-space scale bar 20 across the front which is formed at the rear into a track 21 for a roller 22 mounted on an arm 23 extending forwardly from and supporting the front of the carriage 12. At the rear is a heavy round cross-rod 24 mounted in the frame 10 on which is slidably supported a cylindrically socketed arm 25 depending from the rear 30 of the carriage 12. The carriage 12 is made rigid by an obtuse-angled cross-bar 26 at the rear and a right-angled cross-bar 27 at the front. A front cross-rod 28 in the frame 10 supports at the left a usual line-end margin-stop 29 provided at the rear with a dual cam 30 for depressing a toothed arm 36 which actuates a signal and a key-lock (not shown). Knobs 31 are mounted on the ends of the platen 13 and may rotate the platen. Letter-space feeding of the carriage 12 is procured by means of a rack-bar 32 supported at the ends on arms 33 which are pivotally mounted in the sides of the carriage 12 on pivot pins 34 (only one of the arms 33 being shown), the right arm 33 being rigidly connected with a carriage-release-lever 35 by means of which, against the tension of a spring 44, the bar 32, which has letter-spacing teeth forming a rack 37, is lifted out of meshing engagement with an escapement pinion 38 which together with a cylindrical collar 39 is mounted rotatably on a shaft 43 (see Figure 4) in the escapement mounting frame 40 of a well-known construction. A ratchet wheel 41, fixed on the escapement shaft, has a tooth 42 for each letter-space. The pinion 38, as clearly shown in Figures 6 and 8, is rotatable forwardly or clockwise with reference to the ratchet wheel 41 but the pinion 38 is prevented from rotation in the counter-clockwise direction with reference to the wheel 41, or in other words the ratchet wheel 41 controls the feed of the bar 32 from right to left, under control of the spring drum 17, but the bar 32 is free to move to the right with the pinion 38, to the right being in the carriage-return direction; means permitting the foregoing relative motion and locking are a pair of pawls 45 oppositely disposed and pivotally mounted on the front side of the ratchet wheel 41 to engage the pinion 38 at an angle inclined in the clockwise direction. Each pawl 45 is held in yielding engagement in the clockwise rotation of the pinion and in lock-

ing engagement in the counter-clockwise rotation of the pinion 38 by loop springs 46 on one end of each bearing on the back of a pawl 45 and the other end being held by a stud 47 on the front side of the ratchet wheel 41. A dog rocker 48 is pivotally mounted in the escapement mounting frame 40 and supports the usual fixed dog 49 and the usual limber dog 50 to which is attached a pull spring 51 which tends to draw the limber dog 50 into engagement with a letter-space positioning stop arm 52 mounted on the rocker 48. A check dog 53 (see Figure 4) is pivoted on the rocker 48 to the right of the fixed dog 49 and is held in a vertical position, but yieldable away from the dog 49 along the guide arm 55 mounted on the dog 49, when engaged by the right side of a tooth 42, but also exactly stopping the ratchet wheel when the latter is advanced clockwise one letter-space. A thumb-piece 56 may be used for the facile return of the carriage 12 to the banking position in which a counter-stop 57, mounted on a lever 58 pivoted on a screw 59 on the cross-bar 27 of the carriage 12 and held in engageable position by a spring 60, engages a margin-stop 61 adjustably mounted on the rod 28 and a banking rod 62, both of said rods being mounted in the front of the frame 10. An arm 63, releasable by the finger-piece 64, has teeth 65 which engage notches 66 in the rod 62 to secure the margin-stop 61 in any adjusted position on the rod.

Referring now to Figure 7, when the carriage 12 is returned to the banking position it has attained often considerable momentum when it has reached the banking position, this momentum tending to move the carriage after stops 57, 61 are engaged at the front, thereby carrying along the rear of the carriage 12 to produce a twisting of the carriage to the position shown in Figure 7 in dot-and-dash lines. Such a twisting motion carries along the rack-bar 32 also and causes the pinion 38 to turn so that the initial printing position, after the torsion in the carriage has corrected itself, is one letter-space to the left of the letter-space normally predetermined by the position of the margin-stop 61. To overcome this faulty operation and to exactly position the carriage for the predetermined letter-space in each and every line I provide a novel escapement pinion and carriage-rack locking device shown herein applied to a typewriter equipped with an electrically operated automatic carriage return.

Referring to Figure 1 a motor 70 drives a shaft 71 on the end of which, within a housing 72, is mounted a worm-gear 73 which meshes with and rotates a gear wheel 74 fixed on the rear end of a shaft 75 journaled in a bearing 76 which is supported in the frame 10. A clutch comprises a rear jaw 77 pinned against turning on the shaft 75 and a front jaw 78 rotatably and slidably mounted on the shaft 75. The jaw 78 mounts a pinion 79 which meshes with a carriage rack 80 supported on arms 81, one of which is shown at the right depending from the rear carriage cross-bar 26. The pinion 79 and the rack 80 are in continuous mesh. Secured on the front of the jaw 78 and rotatable therewith on the shaft 75 is a centrally grooved cylindrical guide 82 in which lies the upper end of a forwardly and rearwardly oscillatable actuating arm 83 mounted at its lower end on the rock-shaft 84 which is journaled transversely in the lower front end of the bearing 76. A depending arm 86 is fixed on the rock-shaft 84 and by means of a link 87 actuates an arm 88 fast on a rock-shaft 89 transversely mounted on the frame 10. An arm 90 depends 75

from and is fast on the rock-shaft 89 and at its lower end is pivotally connected with a rearwardly extending arm 91 which opens and closes a switch 92 in the electrical circuit to the motor 70. 5 As shown in Figure 3 the switch 92 is open as well as the clutch 77, 78. To the lower end of the arm 88 is pivotally connected a forwardly extending keeper arm 94 which passes through a slot 95 in the transverse keeper plate 96 and which is secured in the forward position shown in Figure 3 by a notch 97 in the lower edge of the arm 94 and a spring 98 pinned to the arm 94 and to the inside of the frame 10. A key 99 is pivotally mounted in the frame 10 on a lever 100 which 10 has an upstanding inner end 101, on which a spring 102 is positioned to hold the key 99 in the upright position with the rear edge of the inner end 101 engaging a stop pin 102 mounted in the frame 10. A second stop-pin 103 limits the depression of the key 99. It is apparent that, when the arm 94 is locked, in the position shown, by the keeper 96, the switch 92 is broken and the clutch 77, 78 is open, but when key 99 is depressed and the upper end of arm 101 engages a cam 119 15 to disengage the arm 94 from the keeper 96, the carriage 12 is electrically returned.

Mounted on the right end of the rock-shaft 84 is a forwardly projecting arm 104 on which is pivotally mounted a depending link 105 the lower end of which is pivotally connected with the rear end of a lever 106 rockingly mounted in a frame bracket 107 by means of a pivot rod 108. On the forward end of the rocking lever 106 is mounted a vertical link 109 the upper end of 20 which is twisted into the vertical transverse plane and is apertured by a central vertically elongated slot 110 which slidably confines a screw 111 which is fastened in the lower arm of a bell-crank 112, pivotally mounted on an arm 113 25 which in turn is mounted in the end arms 114 of a bracket 115 by means of screw-set collars 116. The bracket 115 is mounted on the frame 10. It is now clear that when the key 99 is depressed the notch 97 is lifted from the keeper 96 (see Figure 3) the switch 92 is made and the clutch 77, 78 is engaged, but that when the bell-crank 112 is moved clockwise to the extreme right position shown in Figure 6 the switch 92 and the clutch 77, 78 are broken and the carriage stopped 30 in an initial letter-space. A forwardly extending pin 117 mounted on the banking rod 62 is locked for movement in and with a slot 118 in the top of bell-crank 112. A spring 120 tied to a depending post 121 and to the frame 10 tends to hold the banking rod 62 in the extreme left 35 position.

The rod or arm 113 which is fixedly secured to the bell-crank 112 and is rockable in the bracket arms 114 may be extended rearwardly 40 and downwardly in the form of a crank 125 the upper rear end 126 of which terminates below the bearing axis of the rod 113 so that a transversely and horizontally positioned arm 127 pivoted on the upper rear end 126 of crank 125 is moved to the left when the banking rod 62 moves to the right to rotate the bell-crank 112. In other words as the counter-stop 57 and counter-stop 61 engage in banking position the arm 127 is moved to the left, and the reverse is also true so 45 that as the bell-crank 112 oscillates the arm 127 moves in the opposite direction.

In Figures 1 and 6 it is seen that the banking rod 62 carries a fixed collar 128 on a reduced extension 124 of the banking rod 62, the extension 50 having a slidable bearing in a round aperture in

the top of the frame 10. The collar 128 is spaced to the left of the frame 10, as shown in Figure 1, when the stops 57, 61 are in the initial engaging position, so that the banking rod 62 can slide to the right until the collar 128 engages the side of the frame 10 as shown in Figure 6. This motion causes an opposite or leftwards motion in the arm 127 to actuate my improved mechanism for preventing a faulty setting of the carriage 12 when returned to banking position with excessive carriage momentum. The arm 127 has an elongated central slot 129 and terminates at the left in a narrower extension 130 which has near its outer end an upstanding stop 131. A top ear 132 and a bottom ear 133 are fast on the top and bottom of an arm 134 and secure the arm 134 and the extension 130 together slidably one to the other. Another top ear 135 to the right of ear 132 and another bottom ear 136 on the arm 134 secure the arm 127 in sliding contact with arm 134. The arm 134 also has an elongated slot 137 shorter than the slot 129, the left end wall of which has a short central projection 138 to the right and the right end wall of slot 129 in arm 127 has a central projection 139 to the left longer than the projection 138. A coil spring 140 is mounted in the two slots 129, 137 and secured in position by pushing the ends of the coil spring 140 over the opposed extensions 139, 138 so that the ends of the coil spring 140 5 press against opposite ends of the slots 129, 137, thereby tending to extend the arms 127, 134 with reference to each other, but on the other hand the arm 134 can slide back to the right on the arm 127 against the tension of the spring 140. 55 The ear 132 engages the stop 131 and limits the extension of the arms 127, 134. The left end of the arm 134 is secured by a pivot screw 142 to a pawl 143 which is pivoted on the escapement mounting 40 by a pivot screw 144. It is now obvious that as the arms 127, 134 move to the left the pawl 143 moves into engagement with a ratchet-tooth wheel 145 to prevent rotation of the wheel 145 in a clockwise direction. The wheel 145 which is fixed on the outer end of the cylindrical collar 39 and is therefore rotatable with the pinion 38 is locked against slipping off the end of the escapement shaft 43 by means of the head of a screw 146. The pinion 38, the collar 39, and the ratchet 145 form an integral 60 rotatable unit. The pawl 143, when engaged with the ratchet wheel 145, therefore locks the escapement pinion 38 against clockwise or carriage-return rotation, and when engaged after the manner of my invention concurrently and concomitantly with the arresting of the carriage by the engagement of the carriage and frame margin-stops in banking position it prevents overthrow of the pinion 38 and therefore overthrow of the carriage 12 one letter-space to the right of letter-space position predetermined by the setting of the margin-stop 61. The effect of this carriage overthrow is shown in Figure 7 where a type 15 is shown striking one letter-space to the left of the predetermined margin indicated by the extreme left "X" 's in the two imprinted lines on the copy-sheet 14. 65

On the other hand if the carriage-rack 37 is altogether disengaged in the banking position so that the rack 37 no longer meshes with the pinion 70 38 the carriage may come to a final stop one letter-space to the left of the initial banking position predetermined by the stops 57, 61. The effect of such a jumping of the carriage would be to have the first letter-imprint in a line in the 75

second letter-space position from the left shown on the copy-sheet 14. To prevent the disengagement of the carriage-rack 37 from the pinion 38 a hook 150, which may overlie the rack-bar 32 5, is provided on an arm 151, the latter being pivotally mounted on a screw 152 which is secured on a support 153 in the frame 10. The pivotal mounting of the hook 150 is such that it normally lies to the rear of the rack-bar 32 10 so that the rack 37 may be lifted clear of the pinion 38 by depressing the carriage release lever 35. A pin 154 is secured in the lower horizontal end of the arm 151 and projects forwardly into and through an inclined slot 155 in the arm 134 15 the inclination of which is upwardly to the left and downwardly to the right so that when the arm 134 is moved to the left the top of the slot cams down the pin 154 and therefore the hook 150 to lock the rack-bar 32 against rising (the 20 free position of the rack-bar 32 being shown in Figures 1 and 3 and the locked position in Figure 6). When the arm 134 is restored to the right the lower edge of the slot 155 cams up the pin 154.

25 The spring 143 holds the pawl 143 in engagement with the ratchet wheel 145 irrespective of slight irregularities from precision in manufacture and furthermore prevents any stresses or strains on the parts in case of an unusually great banking thrust which compresses the spring 140.

30 The spring 98 and the spring 120 tend to restore the pawl 143 and the hook 150 to inoperative position by moving the upper rear end 122 of the crank 125 to the right.

35 Referring to Figure 4, the check pawl 53 is shown in the normal vertical position in which it is maintained, yieldably to the right, by the spring 54. As the carriage-rack 37 feeds to the left the pinion 38 is rotated counter-clockwise 40 and so likewise the ratchet wheel 41, under control of the escapement dogs 49, 59, turns counter-clockwise in letter-space feeding of the rack 37 to the left. Each tooth 42 engages the pawl 53 on the left side and tilts it back to the right as 45 it passes over the pawl 53.

Referring to Figure 2 the ratchet wheel 41 is shown in the condition obtaining when the carriage-rack 37 is at the extreme right, when the initial margin-stop 51 is engaged by the carriage stop 57, in which condition the spring-retracted limber-dog 58 engages the right side of a tooth 42 to check counter-clockwise rotation of the ratchet-wheel 41 and the pawl 53 engages the left side of another tooth 42 to check clockwise rotation of the ratchet-wheel 41, thereby assuring 50 that when the rack 37 drops back to the left, the letter-space and a fraction provided by the adjustment, the position of the platen-carriage 12 is always uniform with reference to the banking 55 margin-stop 51. The letter-space drop is provided by the rotation of the wheel 41 a single tooth, and the fraction of the play between the pawls 45 and the engaging teeth of the pinion 38.

60 Variations may be resorted to within the scope of the invention, and portions of the improvements may be used without others.

Having thus described my invention, I claim:

1. In a typewriter having a frame and a carriage reciprocatorily mounted thereon, in combination, an escapement pinion rotatably mounted on the frame, a rack mounted on the carriage and normally engaging said escapement pinion, a margin-stop adjustable on the frame, a counter-stop on the carriage, said stops determining the initial letter-space position of a line of typing,

means actuated by the margin-stop for locking the escapement pinion against overthrow of the carriage to a printing position to the left of the initial predetermined letter-space position, and means for concomitantly locking the rack in mesh with the pinion. 5

2. In a typewriter having a frame and a carriage reciprocatorily mounted thereon, in combination, an escapement pinion rotatably mounted on the frame, a rack mounted on the carriage 10 and normally engaging said escapement pinion, a margin-stop adjustable on the frame, a counter-stop on the carriage, said stops determining the initial letter-space position of a line of typing, and means for preventing faulty operation of the mechanism in which the initial position of the carriage does not correspond with the setting of the margin-stop, comprising a pivoted arm oscillatable from a position over a carriage-rack away from the carriage-rack and means actuated by said margin-stop for oscillating said arm. 20

3. In a typewriter having a frame and a carriage reciprocatorily mounted thereon, in combination, an escapement pinion rotatably mounted on the frame, a rack mounted on the carriage 25 and normally engaging said escapement pinion, a margin-stop mounted for limited movement on the frame, a counter-stop on the carriage, said stops determining the initial letter-space position of a line of typing, and means actuated by the frame margin-stop for securing the carriage against faulty initial banking positioning to initial printing position at either side of the initial predetermined letter-space position, comprising a pawl movable into and out of locking engagement 30 with the escapement-pinion, an arm for locking the carriage-rack in mesh with the escapement pinion, and an arm for concurrently moving said pawl and said first-mentioned arm. 35

4. In a typewriter having a frame and a carriage reciprocatorily mounted thereon and having a feed-rack, in combination, an escapement having a shaft mounted in the frame, a ratchet rotatably mounted on the shaft, a pinion fixed on the shaft, a pawl pivoted on the ratchet and engaging said pinion to permit independent rotation of the pinion and the shaft clockwise only, a ratchet fixed to turn with the escapement pinion, a pawl movable into engagement with said last-named ratchet to stop carriage-return rotation of said pinion, a margin-stop on the carriage, a margin-stop on the frame, and a device actuated by the engagement of the carriage margin-stop and the frame margin-stop to move said last-named pawl into engagement with said last-named ratchet. 50

5. In a typewriter having a frame and a carriage mounted for reciprocator movement thereon, in combination, an escapement pinion rotatably mounted on the frame, a rack mounted on the carriage and normally in mesh with said escapement pinion, a margin-stop mounted for limited movement on the frame, a counter-stop on the carriage, said stops determining the initial letter-space position of a line of typing, and means actuatable by movement of said margin-stop for locking said rack in mesh with said escapement pinion. 60

6. In a typewriter having a frame and a carriage mounted for reciprocator movement thereon, in combination, an escapement pinion rotatably mounted on the frame, a rack mounted on the carriage and normally in mesh with said escapement pinion, a margin-stop mounted for limited movement on the frame, a retractile 70

spring for said margin-stop, a counter-stop on the carriage, said stops determining the initial letter-space position of a line of typing, and means actuatable by advance movement of said 5 margin-stop for momentarily locking said rack in mesh with said escapement pinion, said locking means being releasable by retraction of said margin-stop.

7. In a typewriter having a frame and a carriage mounted for reciprocatory movement thereon, in combination, an escapement pinion rotatably mounted on the frame, a rack mounted on the carriage and normally in mesh with said escapement pinion, a margin-stop mounted for 10 limited movement on the frame, a retractile spring for said margin-stop, a counter-stop on the carriage, said stops determining the initial letter-space position of a line of typing, and means actuatable by advance movement of said 15 margin-stop for locking the escapement pinion against overthrow of the carriage to a printing position to one side of the initial predetermined position, said locking means being releasable by said spring incident to the retraction of said 20 25 margin-stop.

8. In a typewriter having a frame and a carriage mounted for reciprocatory movement thereon, in combination, an escapement pinion rotatably mounted on the frame, a rack mounted on the carriage and in mesh with said escapement pinion, a margin-stop mounted for limited movement on the frame, a counter-stop on the carriage, said stops determining the initial position of a line of typing, a power-actuated carriage-return mechanism including control means, and means actuatable by said margin-stop for concomitantly operating said control means to disable said carriage-return mechanism and locking the escapement pinion against overthrow of 30 35 40 the carriage to a printing position to one side of the initial letter-space position.

9. In a typewriter having a frame and a carriage mounted for reciprocatory movement thereon, in combination, an escapement pinion rotatably mounted on the frame, a rack mounted on the carriage and in mesh with said escapement pinion, a margin-stop mounted for limited reciprocatory movement on the frame, a counter-stop on the carriage, said stops determining the initial position of a line of typing, a power-actuated carriage-return mechanism including manually settable control means resettable by said 45 50 55 margin-stop and means actuatable by said margin-stop for concomitantly operating said control means to disable said carriage-return mechanism and locking the escapement pinion against overthrow of the carriage, said locking means being releasable during retraction of said margin-stop, said disabling and locking means having a lost motion connection to permit retraction of said 60 margin-stop with said control means in reset condition.

10. In a typewriter having a frame and a carriage mounted for reciprocatory movement thereon, in combination, an escapement pinion rotatably mounted on the frame, a rack on the carriage and normally engaging said pinion, a margin-stop mounted for limited movement on the frame, a counter-stop on the carriage, said stops determining the initial letter-spacing position of a line of typing, and means actuatable by movement of said margin-stop for securing the carriage against faulty initial banking position, said means comprising an arm swingable to abut said carriage-rack for locking same in mesh with said escapement pinion. 5 10

11. In a typewriter having a frame and a carriage mounted for reciprocatory movement thereon, in combination, an escapement pinion rotatably mounted on the frame, a rack on the carriage and normally engaging said pinion, a ratchet wheel rotatable with said pinion, a margin-stop mounted for limited movement on the frame, a counter-stop on the carriage, said stops determining the initial position of a line of typing, a crank arm actuatable by said margin-stop, a link actuated by said crank arm, a member 15 20 25 movable into and out of engagement with said rack, and a pawl swingable to engage said ratchet wheel, said link being operatively associated with said pawl and rack-locking member to concomitantly actuate same. 30

12. In a typewriter having a frame and a carriage mounted for reciprocatory movement thereon, in combination, an escapement pinion rotatably mounted on the frame, a rack on the carriage and normally engaging said pinion, a ratchet wheel rotatable with said pinion, a margin-stop mounted for limited movement on a frame, a counter-stop on the carriage, said stops determining the initial position of a line of typing, a crank arm actuatable by said margin-stop, 35 40 45 a link actuated by said crank arm, a member movable into and out of engagement with said rack, and a pawl swingable to engage said ratchet wheel, said link being operatively associated with said pawl and rack-locking member to concomitantly actuate same, said link being yieldable in one direction whereby to yieldably urge said pawl and locking member into engagement.

13. In a typewriter having a frame and a carriage mounted for reciprocatory movement thereon, in combination, an escapement pinion rotatably mounted on the frame, a rack mounted on the carriage and normally in mesh with said escapement pinion, a margin-stop mounted for limited movement on the frame, a counter-stop on the carriage, said stops determining the initial position of a line of typing, a power-actuated carriage-return mechanism, and means actuatable by said margin-stop for concomitantly disabling said carriage-return mechanism and locking said 50 55 60 rack in mesh with said pinion.

ALFRED G. F. KUROWSKI.
